UNITED STATES PATENT OFFICE.

EDWARD JAMES RICHMOND, OF CHESAPEAKE, MISSOURI.

MACHINE FOR FILING SAWS.

SPECIFICATION forming part of Letters Patent No. 372,766, dated November 8, 1887.

Application filed May 10, 1887. Serial No. 237,761. (No model.)

To all whom it may concern:

Be it known that I, EDWARD JAMES RICHMOND, a citizen of the United States, residing at Chesapeake, in the county of Lawrence and 5 State of Missouri, have invented a new and useful Improvement in Machines for Filing Saws, of which the following is a specification.

My invention relates to an improvement in 10 machines for filing saws; and it consists in the peculiar construction and combination of devices, that will be more fully set forth herein- after, and particularly pointed out in the claims.

15 In the drawings, Figure 1 is a perspective view of a saw-filing machine embodying my improvement. Fig. 2 is a vertical longitudinal sectional view of the same, taken on the line *x* *x* of Fig. 3. Fig. 3 is a vertical trans- 20 verse sectional view taken on the line *y* *y* of Fig. 2.

A represents a table, which is supported upon standards or legs B, arranged at the 25 ends of the table and connected together in pairs near their lower ends by means of cross-bars C. D represents a longitudinal bar which has trunnions formed at its ends and journaled in openings made in the center of the bar C. On the said longitudinal bar is secured a 30 treadle, E.

From the under side of the table A depends a pair of boxes, F, in which is journaled a horizontal longitudinal shaft, G. The said shaft is provided near its outer end with a 35 crank-arm, H, which is connected to the treadle by means of a pitman, I. The inner end of the said shaft is provided with a crank-arm, K, and at the extreme outer end of the shaft is a fly-wheel, L.

40 M represents a wrist-pin, which projects from the end of the crank K, and on the said wrist-pin is journaled a block, M'.

On the upper side of the table A, at the center thereof and at its front edge, is secured a 45 transverse plate, N, which is provided with a pair of parallel tubular guides, O, that project transversely nearly across the table. The said plate N has its outer end pivoted to the table-top by means of a bolt, P, and thereby 50 the inner end of the plate is adapted to swing

toward either end of the table, for the purpose to be hereinafter explained.

R represents a yoke, which is arranged on the upper side of the tubular guides of the plate N, and the ends of the said yoke are 55 connected to the table-top by means of bolts S.

T represents the cross-head, which extends vertically from the inner edge of the table A, and the said cross-head is provided with a pair of parallel horizontal arms, U, that work 60 longitudinally in the guide-tubes O of the plate N. The lower end of the cross-head is connected to the block M on the wrist-pin of the crank K by means of a pitman, V. The rear end of the said pitman is bifurcated, and 55 is engaged by trunnions W, which project from the sides of a block, X, pivoted on the lower end of the cross-head. By this means the cross-head is adapted to turn with the plate N.

To the vertically-projecting upper end of the cross-head is pivoted an arm, Y, which is adapted to move in a vertical plane, and is provided at its outer end with a right-angled extension, Z, which projects upwardly therefrom. On the upper side of the said arm is a 75 tubular guide, A', the front end of which communicates with an opening made in the extension Z.

B' represents a file-clamp, which is provided 80 with a rearward-extending arm, C', adapted to fit in the tubular guide A', and has a forwardly-projecting arm, D', which is arranged to one side of and out of line with the arm C'. In the front end of the latter is made a socket or 85 recess, E', adapted to receive the reduced portion of the rear end of the file F'.

G' represents a block, which is adapted to slide on the arm D', and is clamped thereto at any desired adjustment by means of a set- 90 screw, H'. The lower end of this block is provided with an opening, which aligns with the recess or socket E', and through the said opening extends the front end of the file. By making the block G' longitudinally adjustable on 95 the arm D' the file-holder is adapted to secure a file of any size. The arm C' is adapted to turn in the tubular guide A', so as to tilt or incline the file to any desired angle according to the inclination of the edges of the saw-teeth to 100

be filed, and the said arm C' is secured to the arm Y by means of a set-screw, I', which permits the file-holder to be clamped at any desired longitudinal adjustment or lateral inclination.

K' represents a supporting spring, which projects upward and rearward from the plate N, and the said spring is adapted to support the arm Y. The free end of the plate N has an index, L', which is arranged to sweep over a graduated scale, M', made on the upper side of the table A, and thereby indicate exactly the angle to which the plate N, and consequently the file-holder and file, is turned.

15 On the rear edge of the table A is secured a longitudinal flange-board, N', which is arranged in a vertical position, and is provided on its outer side with a longitudinal groove, O'.

P' represents a saw-clamp, which comprises 20 a pair of longitudinal jaws, R', which are flexibly connected together near their lower edges, so that their upper sides are free to move laterally a slight distance toward and from each other, and are thereby adapted to receive 25 and clamp a saw-blade between the jaws R', as shown at Figs. 1 and 3. One of the jaws R' is provided on one side with a projecting-tongue, S', which enters the groove O', and is thereby adapted to guide the saw-clamp longitudinally on the outer side of the flange-board 30 N'. The lower edge of the saw-clamp is provided with a longitudinal rack-bar, T'.

On the under side of the table, at suitable distances apart, are secured transverse arms 35 U', which project beyond the rear side of the table and are provided at their outer ends with brackets V', in which are journaled horizontal shafts W'. On the said shafts are rigidly secured pinions X', which mesh with the rack-bar 40 on the under side of the saw-clamp, and to the outer ends of the shafts are secured levers or arms Y', by means of which the said shafts and pinions may be turned in order to cause the pinions to mesh with the rack-bar and 45 move the saw-clamp longitudinally to successively present the saw-teeth to the action of the file.

Z' represents a pair of U-shaped springs, which have their inner sides secured to the 50 under side of the table, near the rear edge thereof, and the outer vertical arms of the said springs project upward beyond the saw-clamp and are provided at their upper ends with inwardly-projecting studs A', that enter recesses 55 made in the plate or board B' that bears against the outer side of the saw-clamp. These springs serve to keep the board or plate B' normally pressed against the outer side of the saw-clamp and keep the jaws of the latter pressed 60 firmly against opposite sides of the saw-blade.

The operation of my invention is as follows: The spring K' normally raises the arm Y to such a height that the file will be just above the serrated edge of the saw-blade and out of 65 contact therewith. The operator, seated in front of the table, places his feet upon the treadle E, and by means of the said treadle im-

parts rotary motion to the shaft G. This causes reciprocating motion to be communicated to the cross-head and to the file-holder, and the file 70 is thereby reciprocated transversely back and forth across and over the serrated edge of the saw. By placing the right hand upon the arm Y the operator lowers the said arm sufficiently to cause the file to cut into the teeth 75 of the saw and sharpen the same, and by varying this pressure on the said spring-actuated arm the file can be caused to cut the saw-tooth to any desired depth. As the plate N, to which the file O is secured, is adapted to 80 be turned to any desired angle on the table, it will be readily seen that the file may be caused to operate at any desired angle with respect to the saw.

When it is desired to remove the saw-blade 85 from the clamp, the arm Y is first turned to a vertical position on the upper end of the cross-head in order to move the file-holder out of the way of the saw.

Having thus described my invention, I claim—

1. The combination, in a saw-filing machine, of the table, the plate N, pivoted thereon and adapted to turn to any desired angle, the reciprocating cross-head having the arms guided on the said plate, and the file-holder and connections securing the same to the cross-head, substantially as described.

2. The combination, in a machine for filing saws, of the table, the plate N, pivoted thereon, the reciprocating cross-head having the arms engaging the plate to guide the cross-head, the arm Y, pivoted to the cross-head, the file-holder adapted to be secured to the arm, and the spring K', attached to the plate N and 105 movable therewith, the said spring being adapted to support the arm Y, for the purpose set forth, substantially as described.

3. The combination, in a machine for filing saws, of the table, the plate N, pivoted thereon and adapted to turn to any desired angle, the said plate having the guides O, the reciprocating cross-head having the arms guided in the guides O, the arm Y, pivoted to the cross-head and adapted to secure the file-holder, 110 and the spring K', secured to the free end of the plate N and adapted to be turned therewith, the said spring being further adapted to support the arm Y, substantially as described.

4. The combination, in a machine for filing saws, of the reciprocating cross-head, the arm Y, secured thereto, and the file-holder having the arm C' secured to the arm Y, the forward-extending arm D', the socket E', and the movable block G', adapted to be adjusted on the arm D' and provided with the set-screw H', said block having the opening to receive the front end of the file, substantially as described.

5. The combination, in a machine for filing saws, of the table, the shaft G, having the crank-arm K, the box M, secured to the crank-arm by a wrist-pin, the pitman pivoted to the

said box, the plate N, pivoted on the table and adapted to turn thereon, for the purpose set forth, the cross-head having the arms bearing on the said plate and provided at its 5 lower end with a pivoted block with which the outer end of the pitman is pivotally connected, and the arm Y, attached to the cross-head and adapted to secure the file-holder, substantially as described.

In testimony that I claim the foregoing as to my own I have hereto affixed my signature in presence of two witnesses.

EDWARD JAMES RICHMOND.
